UNITED STATES PATENT OFFICE.

CARL VOTTI, OF PHILADELPHIA, PENNSYLVANIA.

LAMP-BURNER.

SPECIFICATION forming part of Letters Patent No. 241,898, dated May 24, 1881.

Application filed February 9, 1881. (No model.)

To all whom it may concern:

Be it known that I, CARL VOTTI, a citizen of the United States, residing at Philadelphia, in the State of Pennsylvania, have invented 5 certain new and useful Improvements in Lamp-Burners; and I do hereby declare the following to be a full, clear, and exact description of the invention, such as will enable others skilled in the art to which it appertains to make and 10 use the same, reference being had to the accompanying drawings, and to letters or figures of reference marked thereon, which form a part of this specification.

My invention relates to the construction and 15 operation of lamp-burners, and has for its object the simplification of their construction and reduction in the cost of manufacture, and, in their use, additional safety and convenience. Its distinctively novel feature is the separability 20 of the operating parts of the burner from the chimney-gallery, which is connected to the lamp in the usual way.

The subject-matter of this application was 25 before the office in a previous application filed March 2, 1880, which has been allowed and abandoned.

In the drawings (two sheets) forming part 30 of this specification, Figure 1 is an elevation of the complete burner when ready for use. Fig. 2 is an elevation of the part of the burner which holds the chimney and which is secured to the lamp. Fig. 3 is an elevation of the interior shell or body of the burner, to which the wick-tube and the ratchet-shaft are permanent- 35 ly attached, and the deflector removably attached, but the deflector is not shown in this view. Fig. 4 is a plan view of Fig. 2. Figs. 5 and 8 are elevations of variations of Fig. 2. Fig. 6 is a top-plan view of Fig. 3. Fig. 7 is 40 a bottom-plan view of Fig. 3, with the disk F removed to show a means of staying or bracing the wick-tube within the body of the burner. Fig. 9 is a top-plan view of Fig. 1. Fig. 10 is a sectional elevation on the line x x in Fig. 9. Fig. 11 is the deflector; and Fig. 12 shows plan 45 views of variations that may be made in the disk F at the bottom of the wick-tube.

Similar letters of reference denote corresponding parts in all the figures.

50 A is the gallery, having vertical arms C, with

notches b between them, an ornamental bead, a, perforations e, and neck J.

B is the interior shell or body, having perforations d, wick-tube E, horizontal chimney-rest H, with perforations f, with a vertical extension 55 perforated at g, and through which the ratchet-shaft D passes; m indicating the button upon the end, and h h h the ratchet-wheels upon the shaft D for actuating the wick.

G is the deflector, having flame-slot c, provided at i, Figs. 10 and 11, with a vertical slot 60 with horizontal continuation k, permitting it to pass down over the projections l, Figs. 3 and 10, and by a partial rotation lock the deflector upon the body B.

K is the opening in the bottom of the gallery A through which the wick depends, and is surrounded by a ledge, s, upon which the disk F rests when the burner is in use.

III are radial arms extending from the wick-tube E to the body B, serving as stays to retain the wick-tube in position.

J J in Fig. 5 are locking-notches at the base 70 of the vertical arms C, to receive the ends of the ratchet-shaft D when it is desired to lock the body of the burner in its place within the gallery A; and n n n, in Fig. 8, are set-screws for retaining a lip-chimney when it is desired to use this variation of my burner.

In use the neck J of the gallery A is screwed 80 into or otherwise secured upon the lamp, and may so remain. The body B, containing the wick-tube, ratchet-shaft, &c., as shown in Fig. 3, having been provided with a wick and having the deflector, Fig. 11, secured upon it, is 85 placed within the circle of vertical arms C of the gallery A, and, passing down, rests upon the horizontal portion of the gallery A, just within the bead a. The ends of the ratchet-shaft D passing between the arms C at the same 90 time reach a resting place at the bottom of the notches b, and the disk F, upon the bottom of the wick-tube, passing down inside the neck J of the gallery, also at the same time reaches a resting place upon the ledge s. By the addition of a chimney, which is placed within the circle of arms C of the gallery A and pushed down until it rests upon the horizontal portion H of the body B, the body B is prevented from displacement by the weight of the chimney 95 100

resting upon it, and also by the exercise upon the outer surface of the chimney of the friction of the arms C. As thus prepared and arranged my burner is ready for use.

5 If it is desired to use the variation of the gallery shown in Fig. 5, the body, Fig. 3, having been put in place within the gallery as described, may be removably secured by a partial rotation, which will cause the ends of the 10 ratchet-shaft D to pass into the locking-notches J J.

If the form of gallery Fig. 8 is used, the fastening of the chimney by means of the set-screws n will hold the shaft D within the shallow 15 notches shown at b b in this figure.

In all the lamp-burners heretofore made that part containing the mechanism for operating the wick has been permanently attached to that portion which was secured to the collar of 20 the lamp. Such construction aided the downward transmission of heat from the flame to the oil contained within the fount, for the reason that the parts of the burner, being rigidly attached to each other, had the conducting 25 ability of a continuous piece of metal.

It will be seen that by my construction, although the same parts are brought into juxtaposition, yet, there being no intimate union of these parts, but little heat is transmitted, and 30 by reason of the admission of the air in its passage to the flame in such manner that the wick-tube is exposed throughout nearly its whole length to the direct action of the air, any tendency to transmit heat is counteracted.

35 I am aware that many devices have been made enabling the filling of the lamp without the removal of the chimney-sustaining portion from the lamp; but in all of these devices the filling-aperture was obstructed by the permanent attachment of the wick-tube within that 40 part of the chimney-gallery which is attached to the lamp. My construction, consisting as it does of two separate structures—one of which may remain permanently attached to the lamp 45 and support the chimney, the other complete in itself, which is removable at will, and by its removal providing an unobstructed avenue for the repleuishment of the lamp—differs radically from its predecessors, and produces, as I 50 have shown, results not possible to the former devices.

I am aware that burners have heretofore been made in which the chimney-gallery was removable from the wick-tube, which, with its 55 appurtenances, remained attached to the lamp. My invention differs from these burners, in this, that while my gallery A remains permanently attached to the lamp, I am enabled to remove entirely, if I so desire, the body B, with 60 all its appurtenances, as shown in Fig. 3, from their position within the gallery A, thus opening an avenue of nearly the size of the collar of the lamp; or I may raise the body B from its resting place far enough to withdraw the 65 disk F from within the neck J, and, still per-

mitting the wick to depend through the opening K, fill my lamp through the opening thus disclosed. This removability of the body B also permits the thorough cleaning of all the operating parts of my burner which are then 70 readily accessible.

My construction, besides facilitating the filling of the lamp and the proper cleaning of my burner, also provides an effectual safeguard against explosion, so often attended with fatal 75

Previously I have shown that my construction prevented the transmission of the heat of the flame to the oil in the lamp, thus reducing 80 the chance for the formation of explosive gases within the lamp; but if, for any reason, such gases should be formed in the lamp, it will be seen, by reference to Fig. 10, that the rapid circulation of the air entering through the perforations e e in the gallery A would tend to 85 cause a movement of the gaseous contents of the fount through the openings h h in the disk F. When rising within the body of the burner they would, before passing through the perforations in the air-distributer B, become so diluted by mixture with the air passing to the burner as to be entire harmless; but even supposing that such a state of facts as would produce an explosion were to occur in my lamp, its only effect when my burner, as illustrated 90 by Fig. 1, was used would be to raise the body of the burner, with the chimney upon it, from its place within the gallery to such a height as to give the exploding gases room to expand, and thus my construction provides an efficient 95 safety-valve, making disaster impossible.

I have shown my burner adapted to receive the draft-inducing devices ordinarily used, whether having what are known as "lip" or "slip" fastenings, as in Figs. 8 and 2. 100

When the form of my burner shown in Fig. 1 is used it is not necessary that the end of the ratchet-shaft D opposite to the button m should project far enough beyond its bearing in the shell B to engage with the arms C; but when the variation shown in Fig. 5 is used it is preferable that it should so project, so that it may pass at both ends into the locking-notches j j.

Having described my invention and its manner of operation, what I claim and desire to secure by Letters Patent, is—

1. A chimney-holder provided with a threaded neck, and adapted to have the burner proper, comprising the cone, the air-distributer, the wick-tube, and the wick-operating mechanism, detachably supported thereon, for the purpose described.

2. The combination of the deflector, the air-distributer having the wick-tube secured thereto, and the chimney-holder, the parts being separable, as described, for the purpose set forth.

3. The combination of the chimney-holder having the gallery and the ledge with the air- 130

distributer having secured thereto the wick-tube, which is provided with the plate, as and for the purpose described.

4. A lamp-burner comprising a chimney-holder and its gallery adapted for attachment to a lamp, an air-distributer carrying a wick-tube, and a cone, the parts being separable from one another, whereby the central portion of the burner may be removed from and the chimney-

holder remain attached to the lamp, for the purpose described.

In testimony whereof I have affixed my signature in presence of two witnesses.

CARL VOTTI.
